CLAIM

The ornamental design for a cake-pop mold, as shown and described.

DESCRIPTION

FIG. 1 is a perspective view showing my new design;
FIG. 2 is a top view thereof;
FIG. 3 is a bottom view thereof;
FIG. 4 is a front side view thereof;
FIG. 5 is a back side view thereof;
FIG. 6 is a right side view thereof; and,
FIG. 7 is a left side view thereof.

(Continued)

The broken lines shown in the drawings are for the purpose of illustrating portions of the cake-pop mold that form no part of the claimed design.
